UNITED STATES PATENT OFFICE.

DONALD G. LUDINGTON, OF MASONTOWN, PENNSYLVANIA.

VALVE LIFTER.

Application filed December 6, 1926. Serial No. 152,953.

This invention relates to improvements in valve lifters embodying among other characteristics adjusting means for adapting a lifter upon the various forms of valves in 5 different make of motors.

Another object of the invention comprehends a lifting member carried by the operating lever adapted for engagement with a spring cup and to receive a portion of the 10 valve stem and adapted for upward traveling movement upon similar movement imparted to the operating lever.

A further object contemplates a locking dog carried by the operating lever adapted 15 for reception within cut out portions in the lifting member to lock the device in a given position while extracting a valve pin.

More specifically stated a finger engaging element is carried by the imparting dog to 20 permit releasing of the latter.

With the above and other objects in view the invention further consists of the following novel features and details of construction to be hereinafter more fully described and 25 pointed out in the appended claims.

In the drawings:

Figure 1 is an elevation of the invention partly in section while in use, and

Figure 2 is a perspective view of the invention.

Referring to the drawing in detail wherein like characters of reference denote corresponding parts, the reference character 10 indicates a portion of the motor vehicle, 11 the 35 valve guide sleeve, 12 a valve stem adapted for reciprocatory movement therein and 13 and 14 the valve spring and cup therefor. The conventional form of valve pin is indicated 15. All of the above is of the usual 40 construction incident to that of valve mechanisms which form no part of the application for letters-patent but which are merely mentioned for purposes of illustration in bringing forward the novel advantages of 45 the above entitled invention.

In carrying out my invention I provide an operating lever 16 which includes long and short elongated slots 17 and 18 respectively, disposed axially of the longitudinal center 50 of the operating lever. A pin 19 carried adjacent one end of the operating lever 16 is adapted for engagement with the cylinder block of the engine. The forward end of the operating lever is provided with a flattened portion 19' tapered longitudinally thereof

and conforming to the level of the valve heads to lie flush therewith. An L-shaped lifting member 20 has the upper end and vertical leg thereof extending upwardly through the long elongated slot 17. A pin 21 carried

by the operating lever 16 within the elongated slot 17 is adapted for selective reception within any one of a plurality of cut out portions 22 provided in the forward side edge of the lifting member 20. The 60 offset or transverse leg of the lifting member 20 provides a fork portion 23 adapted to receive the valve stem 12 and to seal the valve cup 14 upon the upper side thereof. Said fork portion is disposed in direct alignment with the pin 19 carried upon the adjacent forward end of the operating lever 16 when said pin is called into use. A locking dog 24 pivotally mounted within the slotted portion 18 terminates to provide a 65 forwardly projecting reduced extension 25 which is adapted to be positioned within any one of a plurality of cut out portions 26 disposed at spaced intervals upon the rear side edge of the L-shaped lifting member 20 70 to lock the device in position; substantially as illustrated in Figure 1 of the drawing to permit the removal of the valve pin 15.

A hook 27 carried by the locking dog 24 75 serves as a finger engaging portion to release the locking dog 24 from the lifting member 20 when the operating lever 16 is pushed upwardly.

The invention is susceptible of various 80 changes in its form, proportions and minor details of construction, and the right is herein reserved to make such changes as properly fall within the scope of the appended claims.

Having thus described the invention, what I claim as new is:

1. A valve lifter, comprising an operating lever, adapted to be engaged upon the top of the valve, an L-shaped lifting member, adapted for engagement with the valve spring seat, one edge of said lifter member 100 being provided with a series of notches and said operating lever having a transverse element selectively engageable with said notches, the other edge of said L-shaped lifting member being provided with a series of notches, and a retaining dog, pivotally suspended from the operating lever and detachably engageable with a selective one of the second named series of notches.

2. A valve lifter, comprising an operating 110

lever, adapted to be engaged upon the top of the valve, an L-shaped lifting member adapted for engagement with the valve spring seat, one edge of said lifter member being provided with a series of notches and said operating lever having a transverse element, selectively engageable with said notches, the other edge of said L-shaped lifting member, being provided with a series of notches, and a retaining dog, pivotally suspended from the operating lever and de-

tachably engageable with a selected one of the second named series of notches, the operating lever having an element thereon, engageable with a cylinder block for positioning the lever with respect to the valve, and said dog having a handle element thereon, whereby it may be withdrawn from engagement with the lifting member. ¹⁵

In testimony whereof I affix my signature.

DONALD G. LUDINGTON.
